UNITED STATES PATENT OFFICE.

MAX F. ABBÉ, OF NEW YORK, N. Y.

TUBULAR BALL-MILL.

No. 818,211.

Specification of Letters Patent.

Patented April 17, 1906.

Application filed March 23, 1905. Serial No. 251,601.

To all whom it may concern:

Be it known that I, MAX F. ABBÉ, a citizen of the United States, residing at New York city, Manhattan, county and State of New York, have invented new and useful Improvements in Tubular Ball-Mills, of which the following is a specification.

This invention relates to an improved tubular ball-mill, and more particularly to means for supporting and simultaneously driving the mill, means for feeding the material to be ground, and means for discharging the pulp or ground material.

By my invention the power for operating the mill is reduced, a uniform feed and discharge is effected, and the pebbles used for grinding purposes may be readily removed and replaced.

In the accompanying drawings, Figure 1 is a side elevation of a tubular ball-mill embodying my invention; Fig. 2, an end view thereof; Fig. 3, a longitudinal section through the ingress-head of the mill; Fig. 4, a cross-section on line 4-4, Fig. 3; Fig. 5, a longitudinal section through the egress-head; Fig. 6, a cross-section on line 6-6, Fig. 5, showing an imperforate gate; Fig. 7, a detail of a slotted gate; Fig. 8, a longitudinal section of a modification of the egress-head on line 8-8, Fig. 9; Fig. 9, a cross-section on line 9-9, Fig. 8; Fig. 10, an inner view of part of the ingress-head, showing the ingress-gate; Fig. 11, a section on line 11-11, Fig. 10; Fig. 12, a detail of part of the ingress-head, showing the segmental slide; Fig. 13, a top view thereof, and Fig. 14 a cross-section on line 14-14, Fig. 12.

The letter A represents the rotatable drum or cylinder of the mill, containing the pebbles a, as usual. The cylinder A is suspended from a driving-shaft b, which is supported in bearings b' and carries the driving-pulley b². The means for suspending the cylinder A from shaft b consist of endless ropes or chains c, passing over alined pulleys a² b³ of the parts A and b, respectively. By the construction described the shaft b assumes the dual function of supporting the cylinder A and of rotating it.

If the shaft b is rotated to move the ropes in the direction of the arrows x, the cylinder is slightly deflected sidewise, as shown in Fig. 2. The upward runs of the ropes having a tendency to lift the cylinder will effect a slackening of the downward runs along their lines of engagement with the cylinder, as at c'. In this way a tendency is imparted to

the cylinder to roll toward the slack—i. e., in the direction of the rotation imparted to it by the ropes—so that the power necessary for operating the mill is considerably reduced. Means are provided for sustaining the cylinder while at rest in its deflected position, and thus maintain the proper engagement between the cylinder and the stationary parts of the mill hereinafter described. These means are shown to consist of a sustaining-shaft d, turning in bearings d' and placed at that side of the cylinder A toward which it is deflected. The cylinder is held to the shaft d by endless ropes e, passing over pulleys a² d² of the parts A and d, respectively. The ropes e are of such a length that they will slack slightly when the mill is operated at normal speed, but will prevent the cylinder from assuming a position vertically below shaft b when the mill is at rest. It is obvious that different means for maintaining the cylinder in its deflected position may be employed.

The ingress-head of the cylinder A is divided by an outer wall f, having manhole f¹, an inner wall f', and an intermediate partition f², into an outer chamber f³ and an inner chamber f⁴. The outer wall f has a central perforation to accommodate the discharge end of a fixed hopper g¹⁰, supported upon a base g¹¹ and serving to feed the material to be ground into outer chamber f³. From this chamber the material enters the inner chamber f⁴ through a segmental opening f⁵ of partition f², made near the periphery of the same. This opening is controlled by a segmental slide g, guided along curved rails f⁶ of partition f². This slide terminates at one end in an inclined deflector g', that serves to direct the material toward opening f⁵. In order to control the size of such opening, the slide g may be locked in different positions by a cross-bar g², engaging a grooved seat g³ of the slide and one pair of opposing notches f⁷ of rails f⁶. A pin or catch g⁴ secures the cross-bar g² in place after having been seated.

Within the inner chamber f⁴ is contained a spiral ingress-conveyer h, which by the rotation of the cylinder gradually lifts the material to be ground from the periphery toward the center of the chamber. The innermost convolute h' of the conveyer h flares inward from partition f² toward inner wall f', which has a central discharge-opening f⁸, encircled by such convolute, or, in other words, the inner end of the conveyer is deflected at an obtuse angle to the main body of the same

so that the cylindrical portion of the conveyer merges into an inwardly-flaring discharge-convolute. In this way the material to be ground is not apt to settle upon the conveyer, but will descend by gravity through opening f^3 into the working chamber a^3 of drum A.

The opening f^3 is controlled by a gate i , having perforations i' of a size to permit the free passage of the material to be ground, but to prevent the escape of pebbles a from the drum. The openings i' are made, preferably, in the form of circumferential recesses and concentric inner slots, Fig. 10, whereby a free discharge of the material is insured.

The gate i is provided with a screw-spindle i^2 , engaging a tapped opening of partition f^2 . The spindle i^2 passes through hopper g^{10} and is supported in the standard g^{11} . During the normal operation of the parts the gate i is closed against its seat in wall f^2 , Fig. 11, so that the material to be ground must pass through the openings i' into chamber a^3 . At the same time the pebbles a , even if covering the gate i , are prevented from entering chamber f^4 .

If it is desired from time to time to charge the drum with a fresh supply of pebbles, the old charge is removed through the egress-head in manner hereinafter described, and then the gate i is opened, Fig. 3, so that the pebbles filled into hopper g^{10} will be carried by the conveyer h , through opening f^3 , into working chamber a^3 .

The egress end of drum A may be either provided with a head, as shown in Figs. 5 and 6, which is used for wet grinding, or with a head, as shown in Figs. 8 and 9, which is used for dry grinding. With the construction shown in Figs. 5 and 6 the head consists of an outer wall j (having manhole j^3) and of an inner wall j' , that form an intervening chamber j^2 . Into a central opening of the inner wall j' is fitted a discharge tube or nipple k , that may be provided with a cock k' . The inlet of tube k is provided with a perforated-end plate k^2 , which permits the free discharge of the suspended ground contents of cylinder A, but prevents the escape of the pebbles. The cock k' should be so set that a uniform liquid-level is maintained, the volume of discharged pulp corresponding substantially to the volume of water introduced into drum A, together with the material to be ground. In lieu of providing the discharge-pipe k with a cock k' a set of interchangeable discharge-nozzles, having bores of different diameters, may be used.

The inner wall j' is provided near its periphery with an opening that may be closed either by an imperforate gate l , Fig. 6, or by a slotted gate m , Fig. 7. The chamber j^2 contains a spiral egress-conveyer n , the inner outwardly-flaring convolute n' of which surrounds tube k . This inner convolute n' ex-

tends from the inner wall j' to the outer wall j of the egress-head, and thence projects beyond the outer wall j . Thus here also the inner end of the conveyer is deflected at an obtuse angle to the main body of the same, so that the cylindrical portion of the conveyer merges into an outwardly-flaring discharge-convolute. If it is desired from time to time to empty the drum A, the gate l is replaced by gate m , so that the unground sediments will be discharged through the latter into chamber j^2 , while the pebbles a are held back. The conveyer n will lift the sediments toward the center of chamber j^2 , from which they are emptied by the convolute n' , the tapering shape of which prevents the settling of the sediments upon the conveyer. After the sediments have thus been discharged the gate m is removed, so that the pebbles will fall into chamber j^2 and be discharged by the conveyer n in manner above described with relation to the sediments.

In Figs. 8 and 9 the egress-head of drum A is composed of an outer wall o and an inner wall o' , that form an intervening chamber o^2 . This chamber contains a spiral egress-conveyer p , having a central outwardly-flaring convolute p' . The inner wall o' is provided, beyond the outer convolute of conveyer p , with a series of radial slits o^3 for the discharge of the ground product from chamber o^2 into chamber o^3 . Within chamber o^2 the ground material is lifted by the conveyer p toward the center of the chamber to be finally discharged through the flaring inner convolute p' . A manhole in wall o' , which is normally closed by a cover o^4 , is opened whenever the pebbles are to be discharged. This manhole is formed near the periphery of wall o' to convey the pebbles to the chamber o^2 , from which they are discharged in manner hereinabove described with relation to the ground material.

What I claim is—

1. A tubular ball-mill composed of a rotatable cylinder, inclosed pebbles, a power-shaft, means for suspending the cylinder from said shaft, and means for rotatably sustaining the cylinder in a deflected position, substantially as specified.

2. A tubular ball-mill composed of a rotatable cylinder, inclosed pebbles, a power-shaft, means for suspending the cylinder from said shaft, a sustaining-shaft journaled sidewise from the cylinder, and means for rotatably connecting the cylinder to the sustaining-shaft, substantially as specified.

3. A tubular ball-mill provided with a spiral ingress-conveyer having an inwardly-flaring central convolute, which merges into the body of the conveyer and is deflected at an obtuse angle from the same, substantially as specified.

4. A tubular ball-mill provided with a working chamber, an ingress-head having a

centrally-perforated inner wall that establishes communication between the working chamber and head, a spiral conveyer within the head the innermost convolute of which surrounds the central opening of the inner wall, a perforated gate controlling said opening, and means for opening and closing said gate, substantially as specified.

5. A tubular ball-mill provided with a working chamber, an ingress-head having a centrally-perforated inner wall that establishes communication between the working chamber and head, a spiral conveyer within the head and having an inwardly-flaring central convolute that surrounds the central opening of the inner wall, a perforated gate controlling said opening, and means for opening and closing said gate, substantially as specified.
10. 6. In a tubular ball-mill, an ingress-head provided with an outer chamber, an inner chamber, an intermediate partition having an opening, and a slide having a deflector and adapted to control said opening, substantially as specified.
15. 7. In a tubular ball-mill, an ingress-head provided with an outer chamber, an inner

chamber having a discharge-opening, a partition intermediate the chambers and having a slide-controlled opening, a spiral conveyer within the inner chamber and having an inwardly-flaring central convolute, and a perforated gate that controls the discharge-opening of the inner chamber, substantially as specified.

35. 8. In a tubular ball-mill, an egress-head having an outer wall, an inner wall, and an intervening spiral egress-conveyer having an outwardly-flaring central convolute intermediate the walls, substantially as specified.

40. 9. In a tubular ball-mill, an egress-head provided with an inner wall, an outer wall, an intermediate chamber, a spiral conveyer within the chamber, a cock-controlled discharge-tube surrounded by the inner convolute of said conveyer, and a perforated plate at the inner end of said tube, substantially as specified.

Signed by me at New York city, (Manhattan,) New York, this 22d day of March, 1905. 5c
